[57] CLAIM

The ornamental design for a playground merry-go-round, substantially as shown and described.

DESCRIPTION

FIG. 1 is a pictorial view of our new design for a playground merry-go-round as seen from a point which is above and to one side of the design.

FIG. 2 is a view, partially broken away, as seen along lines 2—2 and partly in section.

FIG. 3 is a view, partially broken away, as seen along lines 3—3, and particularly illustrating a portion of bottom of my new design. The balance of the bottom of our new design is plain and unornamented.

FIG. 4 is a view, partially broken away, as seen along lines 4—4 of FIG. 1.

FIG. 5 is a view, partially broken away, as seen along lines 5—5 of FIG. 1.
